United States Patent Office

Des. 182,907

Patented May 27, 1958

182,907

DISPLAY RACK FOR TOOLS AND SIMILAR ARTICLES

George P. Lewis, Mineola, N. Y.

Application January 2, 1957, Serial No. 44,374

Term of patent 14 years

(Cl. D80—10)

FIG.1.

FIG.2.

FIG.3.

Fig. 1 is a perspective view of a display rack for tools and similar articles embodying my new design;

Fig. 2 is a rear elevational view of the same, and

Fig. 3 is a side elevational view of the same.

I claim:

The ornamental design for a display rack for tools and similar articles, as shown.
